UNITED STATES PATENT OFFICE.

WILLIAM E. HILL, OF KALAMAZOO, MICHIGAN.

LOG-UNLOADER.

SPECIFICATION forming part of Letters Patent No. 324,840, dated August 25, 1885.

Application filed January 31, 1885. (No model.)

To all whom it may concern:

Be it known that I, WILLIAM E. HILL, a citizen of the United States, residing at Kalamazoo, county of Kalamazoo, State of Michigan, 5 have invented a new and useful Log-Unloader, of which the following is a specification.

This invention relates to that class of devices which are provided with pivoted arms stationed beneath the log and adapted to be 10 pushed against the log by connecting power for the purpose of throwing or moving the log in either lateral direction.

It has for its object an improved construction, substantially as hereinafter described and 15 claimed.

In the drawings forming a part of this specification, Figure 1 is a broken plan elevation, the skidway-floor being in cross-section; Fig. 2, a top view with portions broken away; Fig. 20 3, a broken detail in enlarged perspective; and Fig. 4 is a plan view of an enlarged detail.

The sills D and floor d represent a log-skidway or mill-floor inclining downward each 25 way from a log-trough. In this log-trough is located a log-conveyer, C, in the usual manner. Such conveyers engage the under side of the log L, and are used to convey the log from the river or other place to any desired place in the mill. In this case the log is 30 conveyed to the device for unloading the same out of the log-trough when the logs roll down the skidway on rails f f to the saw or log carriage, as the case may be. (The saw and log carriage not here shown.)

Below the floor d is a bed-beam, E, to which 35 the engine F is centrally pivoted, the engine being thus adapted to tilt during the operation. Beneath the log-trough is a rock-shaft, v, to a pendent arm, e, of which the free end 40 of the engine-piston is pivotally connected.

At each end of said rock-shaft, or at other suitable location, are rigidly connected the double log-levers B. In the drawings these 45 levers are in substantially a U form, and are connected with each other where they are secured to the rock-shaft, the free ends thereof extending on each side up toward the log L. Concaved pockets are formed in the free ends 50 of the levers, and are adapted to retain therein spherical balls a a, in a manner that said balls will turn in the pockets when their exposed periphery comes in contact with the log. The

balls thus retained in the pockets are universal friction-balls. The great advantage of this style of friction devices in the end of the levers is that as they will roll in any direction it matters not what condition of the surface of the log comes in contact therewith, and for the same reason they may be brought in contact with a log while under endwise motion 60 without danger of breaking the levers or friction devices.

As a means of keeping the double lever B in a balanced position, so that neither free end will be liable to conflict with the log when not 65 in operation, I provide two weights, w w, and connect them with the arm e by means of ropes or chains, which pass over pulleys x, connected with any suitable support. Thus the weights, being of the same heft, exert a like purchase on 70 the end of the arm e and keep the double lever in position, as in prior constructions; but it is found necessary to limit the fall of the weights, and in most instances the distance to the ground or floor below the weights is too 75 great to use the floor for a limit. Hence I have made the bearing-blocks of the pulleys over which the chains s s run with an upward projection, through which the chains pass, and provide the chains with a knot or collar, forming stops, which come in contact with said upward projection of the pulley-blocks, and thus 80 limit the fall of the weights, all as shown in Fig. 1. By the means of said limit the rock-levers sooner assume a position at rest. 85

In the operation, by causing the engine-piston to move outward, the rock-shaft is rotated, causing the right-hand free end of the double lever B to engage the log, throwing the same out of the log-trough, when the log rolls down 90 the left-hand incline rails f f. The opposite movement of the piston would of course throw the log in the other lateral direction. During this action the engine F tilts on its pivot to conform to the sweep of the arm e, thus insuring a free positive action by a very simple construction and combination of parts.

I am aware that rock-levers for rolling logs and pivotally-supported engines are not new, *per se*, in this application. I am also aware 95 that the free ends of the rock-levers have heretofore been provided with rollers capable of moving in a single direction under the engagement of the log.

Having thus described my invention, what I claim as new, and desire to secure by Letters Patent, is—

1. An improved log-unloader consisting of a rock-shaft beneath the log-trough, the double rocking levers, and a downwardly-extending operating-lever secured to the rock-shaft, and a horizontal pivoted engine, the free end of its piston pivotally connecting with the free end of the operating-lever, substantially as set forth.

2. The combination of the rock-lever and shaft, the operating-lever projecting from said shaft, means for oscillating the operating-lever, the fixed pulley-blocks having the stop-

projections, pulleys in said blocks, and the weighted chains or ropes connecting the operating-lever passing over the pulleys, and provided with the stops for conflicting with the stop-projections of the pulley-blocks to limit the fall of the weighted end of the chains, substantially as set forth.

In testimony of the foregoing I have hereunto subscribed my name in presence of two witnesses.

WILLIAM E. HILL.
